A. A. MOTHERWELL,
METHOD OF FORMING CRANK SHAFTS.
APPLICATION FILED JULY 23, 1917.

UNITED STATES PATENT OFFICE.

ALEXANDER A. MOTHERWELL, OF FLINT, MICHIGAN, ASSIGNEE TO GENERAL MOTORS COMPANY, OF JERSEY CITY, NEW JERSEY, A CORPORATION OF NEW JERSEY.

METHOD OF FORMING CRANK-SHAFTS.

1,271,605.

Specification of Letters Patent.

Patented July 9, 1918.

Application filed July 23, 1917. Serial No. 132,170.

To all whom it may concern:

Be it known that I, ALEXANDER A. MOTHERWELL, a citizen of the United States of America, residing at Flint, in the county of Genesee and State of Michigan, have invented certain new and useful Improvements in Methods of Forming Crank-Shafts, of which the following is a specification, reference being had therein to the accompanying drawings.

The invention relates to the process of forging crank-shafts and comprises the novel method of forming a multiple crank-shaft, in which the cranks extend in a plurality of planes.

In the drawings:

Figures 1, 2, 3, 4 and 5 show the successive steps of the forging process; and

Fig. 6 is a perspective view of the dies.

In carrying out my improved process, a heated straight bar A of a length slightly greater than the crank-shaft and of a cross-section in excess of that of the finished product, is first subjected to an operation of forming-dies to form therein the double crank throw portions B and B' adjacent to opposite ends and in the same plane. These portions thus formed are then engaged in a die which holds them the same distance apart longitudinally, while the portion intermediate said cranks is stretched and fashioned to form other throws C C' in a different plane. At the same time the first-formed cranks are bent to place the opposite throws thereof in different planes so that at the completion of this second operation the cranks are arranged in three or more different planes. There are also bearing portions intermediate the cranks in axial alignment with each other, and at one end of the shaft there is a projecting portion D.

During this second operation the surplus metal squeezed out from the dies will form a fin E, and the crank is therefore next engaged with a trimming die which removes this fin. After the trimming operation the crank is again placed in the die for performing the next operation which refashions the same to the true form.

In order to form a flange coupling at one end of the crank the projecting portion D thereof is upset with a result that a flange F is formed, as shown in Fig. 5, which completes the forging operation.

In carrying out this process the dies for bending and forming the cranks in both the first and second operations are preferably formed adjacent to each other in a single block. Thus as shown in Fig. 6, G and G' 60 are upper and lower forming die blocks, H and H' are the portions of these blocks for performing the first operation and I and I' are adjacent portions of the blocks for performing the second operation. The proximity of these die portions to each other facilitates the quick transfer from one to the other, which is of great advantage.

What I claim as my invention is:

1. The process of forging crank-shafts, 70 comprising simultaneously die-forging non-adjacent throws in the same plane, re-fashioning said throws to bend the same into different planes, and simultaneously stretching and fashioning the metal intermediate 75 the re-fashioned throws to form one or more additional throws in a different plane.

2. The process of forging crank-shafts, 80 comprising the simultaneously die-forging of a plurality of throws in each of two non-adjacent portions of the blank and all in the same plane, re-fashioning to bend the throws in each of said portions into different planes and while held in this operation stretching and fashioning the metal intermediate 85 said portions to form additional throws in a still different plane.

3. The process of forging crank-shafts, 90 comprising the die-forging of a plurality of throws in each of two non-adjacent portions 95 of the blank, all of said throws being in the same plane, simultaneously redie-fashioning the throws in each of said portions to bend the same into different planes and while held by this operation stretching and die-fashioning the metal intermediate said portions to form additional throws in a still 100 different plane, trimming the blank to remove the fin of surplus metal, and subjecting the same to the dies for the second operation to restore the desired form.

4. The process of forging crank-shafts comprising the die-fashioning of a blank to form therein a pair of non-adjacent double throw cranks, all of the throws being in the 105 same plane, subjecting the formed blank to a second die-fashioning operation for bending the throws into different planes and while retained by said dies stretching the intermediate metal to form additional 110

throws in a still different plane, removing the blank from the dies and trimming from the same the fin of surplus metal, and returning the blank to the dies for the last forming operation to restore the true shape thereto.

5. The process of forging crank-shafts comprising die-forging the blank to form therein a pair of non-adjacent double 10 throws, all of the throws being in the same plane and with a portion at one end of the blank of greater length than at the other, subjecting the blank to a second die-forging 15 operation for bending the throws into different radial planes and while engaged with the dies stretching the intermediate metal to form additional throws in a still different plane, removing the blank from the dies and trimming the same to remove the fin of 20 surplus metal, returning the blank to the dies for the last forming operation to re-

store the true shape thereto, and upsetting the end of greater length to form a flange coupling thereon.

6. The process of forging crank-shafts 25 comprising simultaneously die-forging non-adjacent throws in the same plane, said throws being unequally spaced from the crank-shaft extremity, re-fashioning said throws to bend the same into different 30 planes, and simultaneously stretching and fashioning the metal intermediate the re-fashioned throws to form one or more additional throws in a different plane, and upsetting the end portion of greater length to 35 form a flanged coupling thereon.

In testimony whereof I affix my signature in presence of two witnesses.

ALEXANDER A. MOTHERWELL.
